(57) **CLAIM**

We claim the ornamental design for a substrate for light source of light emitting diode, as shown and described.

DESCRIPTION

FIG. 1 is a front perspective view of a substrate for light source of light emitting diode of the present invention; FIG. 2 is a front view thereof; FIG. 3 is a rear view thereof; FIG. 4 is a first side view thereof; FIG. 5 is a second side view thereof; FIG. 6 is a top view thereof; and, FIG. 7 is a bottom view thereof.

The broken line showing of substrate for light source of light emitting diode is included for the purpose of illustrating environment and forms no part of the claimed design. Additionally, the unevenly broken lines in the drawings define the limits of the claimed design.
